UNITED STATES PATENT OFFICE.

DAVID FREDERICK CARVER, OF NEWARK, NEW JERSEY.

CARD-INDEX.

1,053,009.

Specification of Letters Patent. Patented Feb. 11, 1913.

Application filed July 2, 1912. Serial No. 707,165.

To all whom it may concern:

Be it known that I, DAVID F. CARVER, a citizen of the United States, residing in Newark, in the county of Essex and State 5 of New Jersey, have invented a new and Improved Card-Index, of which the following is a full, clear, and exact description.

My invention is applicable to any of the ordinary forms of cards employed in card 10 index systems, and the main object of my invention is to provide the cards with means whereby they will be caused to present themselves in single succession with adjacent cards so spaced apart at the upper edges 15 that at least the heading of each card can be clearly read in succession. My invention enables the operator to readily control the cards so as to cause them to be thrown forwardly in single succession toward the operator, each moving forwardly, separate and 20 distinct from the one in front and the one behind it.

Index cards of the ordinary form, as is well known, move forwardly in response to 25 the manipulation of the operator, variously spaced, and not infrequently moving two or three together as if a unit, so that the operator is required to exercise care and to deliberately separate the cards with the finger- 30 nail, causing annoyance and loss of time. The action of the ordinary cards, as referred to, in clinging together and frequently moving two or more in close relation, may be due to any one of several causes, 35 of which perhaps one of the most important is the forming of a partial vacuum between the cards. Cards provided with my invention will lie in the box in the usual way, but instead of contacting with one 40 another throughout their whole surfaces, or substantially the whole surface, as ordinarily, they will rest in contact with one another along the top edges only, or possibly for a portion of the back and front 45 surfaces near the top edges. The cards are so formed or provided with such disparting or spacing means that they will be separated from one another at the bottom, and for substantially the whole area, except at 50 the upper ends.

It is a design of my invention to so form the disparting and spacing means as to give the operator control of the amount and extent of the spacing between the cards 55 as they turn over forwardly at the top, the control being effected initially through the

medium of the front card, and then through the collected cards at the front as the examination of the cards progresses, the front card or cards acting as a lever serving to 60 exert rearward pressure against the cards at the lower ends, the spacing device at the bottom reacting against the pressure exerted by the operator, and the resultant of the forces serving to cause the successive 65 cards to rise at the top and be rocked forwardly, describing an arc of a circle at the top, the movement of the cards being such that they will move forwardly with their upper edges quite distinctly spaced 70 apart, but may be maintained in fan-like form. The forward movement of the cards is under the complete control of the operator, so that even after a card has moved forwardly beyond the vertical line, it can nevertheless be held under control until the operator deliberately grasps the card and throws it against those previously examined and collected at the front of the card receptacle. 80

It is also a design of my invention to cause the cards to rise upward at the top, and in effect, to slide vertically, relatively to the card immediately behind, thereby preventing or overcoming the ordinary forces 85 of adhesion, or attraction, or vacuum that tend to cause a clinging action between the cards.

It is a further design of my invention to provide a disparting means of such a character as to exert a force on the cards near the bottom, in a direction tending to turn a card over, with its lower edge as a center. 90

It is also a design of my invention to provide a spacing means that will be sufficiently protuberant beyond the surface of the card to effect the desired spacing, but will occupy a minimum space when the cards are compacted. 95

It is a further design of my invention to provide a disparting means whereby cards for reference or index purposes, can be readily and quickly examined and selected, so that the ones not wanted can be passed readily, and the one desired, can be quickly 100 found. It is a further design of my invention to provide a means of quick and ready reference to index or reference cards, one that can be used with the cards in various sequences, with a few cards or with many; 105 and to provide a card index, from which cards can be taken at will, or inserted as

desired, and of which all are, nevertheless, subject to rapid, ready accurate reference.

The distinguishing features of my invention and the important structural elements 5 characterizing the preferred embodiment which is illustrated as an example, will be more particularly explained in the specific description hereinafter to be given.

Reference is to be had to the accompanying 10 drawing forming a part of this specification, in which similar characters of reference indicate corresponding parts in all the views.

Figure 1 is a longitudinal sectional view 15 of a card box or receptacle with my improved index cards assembled therein; Fig. 2 is a similar view showing the position of the cards as the examination thereof by the operator progresses: Fig. 3 is a perspective view of one form of the card attachment 20 embodying my invention; Fig. 4 is a transverse vertical section of the device illustrated in Fig. 3, and showing a portion of the card to which it is applied; Fig. 5 is a 25 perspective view of an attachment of somewhat different form; Fig. 6 is a transverse vertical section of the device illustrated in Fig. 5 and showing a portion of the card to which it is applied; Fig. 7 is a perspective 30 view of still another form of the attachment embodying my invention; and Fig. 8 is a transverse vertical section of the form of device illustrated in Fig. 7, and showing a portion of the card to which the device is 35 applied.

In giving a practical embodiment to my invention, any suitable receptacle 10 is employed and provided with followers or partition blocks 11, 12, there being a single 40 block employed for a small number of cards and a plurality of such blocks when a large number of cards are employed and arranged to divide the same into groups. Each block may have at the bottom a foot 45 or guide plate 13, as is usual, and provided with a depending member as 14, to engage in one or the other of a series of recesses 15 in the customary manner in adjusting the position of the block or blocks in the 50 box or case 10.

Each index card 16 is given such a form, or is provided with such attachment as will produce a protuberance at the lower edge of the card, at the bottom thereof. It is 55 desirable in practice, that the protuberant portion present a broad surface in order to more or less resist the tendency of the cards to dispose themselves diagonally in the box or receptacle. The protuberant element is 60 indicated generally in Figs. 1 and 2 by the numeral 17. In the form shown in Fig. 3, the piece of paper 18 is curved vertically for the greater portion of its height, from the bottom edge, or near the bottom edge, 65 upwardly, its convex side being presented

at the outside, and the paper is affixed to the card 16 by any suitable means. Preferably adhesive material is applied to the strip of paper, as at 19, along the upper edge, said portion being essentially straight or plane, to firmly adhere to the face of the card 16.

In order that the piece of paper or other element or elements made use of to give the rounding protuberant formation may not have a too rigid and fixed set, which would result in the attachment taking up too much room in the card case, and thus to a great extent, limiting the number of cards in a given space, in practice I provide for making the element or elements resilient; thus the paper strip 18 with a layer of linen as at 20, Fig. 7, applied to the back of the paper strip, is of a character to maintain the desired convexity of outer surface 85 wanted in the paper, as well as giving it some resiliency.

In order to obtain a permanent and increased resiliency greater than that possible with paper, I preferably employ a metallic plate spring, which advantageously is formed of ribbon steel, the spring being indicated by the numeral 21 in Figs. 3 and 4. The spring is curved vertically from the bottom to a point short of the upper end, 95 and said upper end extends straight and is secured by adhesive material or other means to the inner face of the paper strip 18. The adhesive material 19 serves to secure the paper carrying the metallic spring 21 to the 100 rear face of the card 16, the metallic spring being disposed between the said card and the strip 18. By the arrangement shown the resilient paper and the metallic spring are free from each other except at 105 the upper edge, and may readily respond to pressure. The paper presents the necessary area, and moreover, its bottom edge is less likely, when a card is being inserted, to engage an adjacent card and interfere with 110 the ready placing or replacing of the card in the group.

In the form shown in Figs. 5 and 6, the spring 21^a is formed similarly to the spring 21 of Figs. 3 and 4, except that its upper end is in the form of a T-head 21^b. With this form also, the upper portion of the paper strip 18^a is return-bent, as at 18^b, and caused to overlie the T-head 21^b, said return-bent portion of the paper being pasted down, or otherwise secured, to hold the spring 21^a in place. To the exposed face of the return portion of the strip 18, adhesive material may be applied, as at 18^c, as a means for securing the attachment to the card 16.

In the form shown in Figs. 7 and 8, I have illustrated the preferred form of the attachment having the paper strip 18^d provided with a facing 20 of linen as mentioned. With this form also the spring 21^d is curved, 130

and, as in the described forms it is integral at its upper end with a pair of flat metallic members 21^a, one of said flat members being disposed at each side of the central 5 spring element. Thus the metallic attachment is formed of three fingers, of which the central one is curved and those on the outside are flat, and are all integral with the head 21^c, which may be secured to the paper 10 by a separate narrow layer 18^e, which is pasted down over the head 21^c and provided on its exposed face with adhesive material, as at 18^f.

In connection with cards provided with 15 my attachment I prefer to employ a front card 22, which has greater stiffness than the ordinary index usually employed.

With card indexes as described, the cards normally will lie approximately as shown at 20 the right hand compartment of Fig. 1, it being understood that the extent of the bottom spacing of the cards in the drawings is somewhat exaggerated in the interest of 25 clearness. Comparing the group of cards in the compartment at the right of Fig. 1, with the cards in the compartment at the left of said figure, and observing the line or sweep presented by the upper edges of the 30 group of cards at the left, it will be seen that those cards at the front of said group have changed their position; the bottom edges of the cards adjacent to the front of the compartment have been shifted rearwardly from the position shown at the right in said Fig. 35 1 to that shown at the left of said figure. To bring this about the front card 22 is employed as a lever, which explains the reason for its having a comparative stiffness. The employment of the front card 22 as a lever 40 is only during the examination of the front index cards 16, since it will be obvious that the first few cards 16 at the front, after they have been gathered beneath the finger of the operator, as for instance at the left of 45 Fig. 2, will act as a lever to successively shift the bottoms of the next rearmost cards. The operator in moving the bottoms of the front cards rearwardly exerts rearward 50 pressure against the remaining cards at the bottom. In shifting the bottom edges of the cards rearwardly, each card so shifted will have an upward sliding movement relatively to the next rearmost card, which will overcome any ordinary tendency of one card 55 to adhere to another either by reason of a partial vacuum, or from other causes.

There will be a limited number of cards between those collected at the front and the bulk of those remaining unexamined at the 60 rear, the intermediate cards being subject to the resultant of the leverage exerted by the operator by means of the front cards and the reaction of the resilient elements on the rearmost cards. The effect is to dispose the 65 intermediate cards in fan-like form increas-

ingly spaced at the top, whereas all other cards are decreasingly spaced toward the top. Inasmuch as the fan-like formation given the cards is not the result of any suddenly applied force, and is not appreciably 70 affected by a card moving forwardly beyond the vertical line, the intermediate cards are under the complete control of the operator and do not reach a position in succession against the front cards until positively 75 moved against the front cards by the finger of the operator.

In explanation of the employment of a plurality of follower or partition blocks 11, 12, I would state that where too great a 80 number of cards are employed in a group, as I have indicated in Fig. 2, the cumulative force exerted by the disparting and spacing elements, generally designated by the numeral 17, may tend to throw the whole 85 group of rearmost cards forwardly as a body, after the examination of the foremost cards has progressed sufficiently for the total reactive force of the resilient elements to be effective. Thus Fig. 2 purposely 90 includes an excess of cards above the proper number for effective operation of my device, and therefore the few rearmost cards are illustrated as having been rocked forwardly, and are given as an example of the 95 effect that will be produced if a material quantity of cards in excess of the proper number be placed in the compartment. There should not be sufficient cards to cause any of the unexamined cards at the rear to 100 rock forwardly together.

The making of the protuberance on rounding lines facilitates the vertical sliding of one card relative to another, and makes the reactive force of the resilient elements on the rearmost cards more effective in rocking the intermediate cards forwardly with their bottom edges as a center, and the point of effective application of the reactive force of the elements on the group of rearmost cards shifts as a different portion of the rounding surface is presented to the next rearmost card.

The described attachment is applied preferably to the back of the card in order to 115 leave the complete front or face of the card available for entries.

Having thus described my invention, I claim as new and desire to secure by Letters Patent:

1. A spacing and disparting attachment for index cards, comprising a sheet of small area compared with the area of index cards, means for securing said sheet to an index card, and means for giving resiliency to 125 said sheet.

2. A disparting attachment for index cards, comprising a plate spring having a bent portion and an approximately plane end portion, means for securing said plane 130

portion to an index, and an exterior member of greater area than said spring.

3. A disparting attachment for index cards, comprising a spring, and an exterior member of greater area than the spring.

4. A disparting attachment for index cards, comprising a spring; and an exterior member of greater area than said spring, said exterior member having means for 10 curing the complete attachment to an index card.

5. A disparting attachment for index cards, comprising a plate spring, and a sheet of larger area than the spring and serving 15 as a carrier for the spring.

6. A disparting attachment for index cards, comprising a metallic plate spring curved longitudinally and having an approximately plane head portion, and a sheet 20 united to the said head of the spring, the sheet and spring being free from each other except at the said head of the spring.

7. A disparting attachment for index cards, comprising a spring having a plurality of fingers, one of which has a bent protuberance beyond the plane of the remainder of the fingers, and means for affixing the said spring to an index card.

8. A disparting attachment for index 30 cards, comprising a sheet of small area compared to the card, means for securing proper convex form to said sheet, means for maintaining resiliency to said sheet, and means for securing said disparting attachment to 35 an index card.

9. Index means, comprising a plurality of index cards, and a holder having a member forming a backing for the cards, said cards having disparting means thereon near 40 the bottoms of the cards, consisting of resilient elements, tending when placed under compression to react and rock the successive cards forwardly and serving to maintain a plurality of cards in fan-like form, as successive cards are examined and collected at 45 the front.

10. Index means, comprising a plurality of index cards, having thereon means for disparting the cards, said disparting means 50 consisting of resilient elements a sufficient distance below the horizontal center and of sufficient power that the cumulative force of a plurality of these said elements under compressive force exerted from the front,

will rock the successively exposed cards to 55 the vertical position and forwardly of the vertical position.

11. In an index means, a series of index cards and disparting means, consisting of resilient elements disposed between adjacent 60 cards, near the bottom and tending under compression to re-act on the cards to maintain a plurality in fan-like formation.

12. In an index means, a series of index cards, having disparting means consisting 65 of protuberant elements between adjacent cards throughout the series, near the bottoms thereof, and normally disposing the series of cards spaced apart toward the bottom and converging toward the top, the 70 cards being adapted to be moved into closer relation at the bottom below said disparting means, and into fan-like formation with the cards at upwardly diverging angles to each other under the force of rearward pressure 75 applied at the bottoms of the front cards of the series below the disparting means.

13. In an index means, a series of cards, having disparting means, comprising protuberant elements carried by the cards at 80 points only thereon adjacent to the lower edges, the surface of the card from which the element is protuberant being plain and free from protuberances, except the mentioned disparting element. 85

14. An index card having a disparting resilient element near the bottom edge, and a member associated with the said element to yield therewith and presenting a broader surface, the said associated member being 90 held at one edge and free at its opposite edge.

15. An index card, carrying thereon near the bottom, a strip having a free edge, and a spring beneath said strip. 95

16. An index card, carrying disparting means near the bottom, consisting of a sheet of small area compared with the area of the card and affixed at an edge thereof to the card, said sheet having an outward bend 100 and being resilient.

In testimony whereof I have signed my name to this specification in the presence of two subscribing witnesses.
